FOLDING BOX

William Trogman, Chicago, Ill.

Application March 6, 1939, Serial No. 260,037

1 Claim. (Cl. 229—52)

This invention relates to a folding box and has as its principal object the provision of a device of this class which is made from a unitary blank of cardboard or analogous material so formed that it may be folded up from a substantially flat condition to provide a box of truncated pyramidal shape.

Another object is the provision of a folding box of the type described and which includes interlocking tab formations adapted to secure the box in erected condition and facilitate opening and closing of the box.

Another object is the provision of a box which is folded up from a unitary blank in the form of a truncated pyramid, the truncated side portions of which constitute the top of the box and are provided with flaps adapted to interlock with adjoining wall portions to secure the box in closed and assembled condition, the truncated top portion of the box including a handle which is slipped into place from within the box and which is prevented from moving back into the box by a special tongue formation in the truncated top portion.

Other objects, advantages, economies and novel aspects of the improved box structure reside in certain details of construction and the arrangement of parts hereinafter described in view of the annexed drawing, in which:

Fig. 1 is a perspective view of the completed box ready for use;

Fig. 1A is a perspective detail of the handle;

Fig. 2 is a perspective view of the box in partly unfolded condition;

Fig. 3 is a sectionalized perspective view of the box in partly collapsed condition looking in the direction of line 3—3 of Fig. 2;

Fig. 4 is a perspective view of the box in wholly collapsed condition; while

Fig. 5 is a plan view of the box blank in wholly unfolded condition.

The novel box is especially suited for use as a hat box and is of novel construction and appearance as depicted in Fig. 1. The box is in the form of a truncated pyramid having a square base 10 flanked by trapezoidal side walls 11 certain of which side walls 11a and 11b (Fig. 5) have flaps 12 and 13 respectively which fold over to provide the truncated top portion 13a of Fig. 1, side wall 11b and its opposite side 11c having, in addition, the tongues or flaps 14 which fit in between the adjoining trapezoidal members 11 and 11a when the box is erected.

In a preferred method of construction, a blank such as shown in Fig. 5 is cut from cardboard or

analogous material by the usual stamping methods, this blank including the central bottom square 10 with its adjoining trapezoidal side flaps and the defining fold crimps 16 arranged as shown. When the box is formed up from such a blank, the free edge 12a on the flap 12 is joined to the truncated edge 15 of the trapezoidal flap 11 by means such as the adhesive hinge strip 17 (Figs. 1 and 2 also). In this condition, the partly formed blank may be erected to define the box of Figs. 1 and 2, or it may be collapsed into the condition shown in Fig. 4.

In order to secure the box in erected condition for use as such, the other top flap 13 is provided with an outwardly extending flap 18 which constitutes a locking tongue, this tongue having a smaller outwardly extending tab 19 which is adapted to fit into a slot 20 in the side 11c. A semicircular cut 21 in the tongue 18 provides a second locking tongue 22 which is flexed outwardly of the tongue 18 for engagement in another slot 23 in the side wall 11c. A small handling tab 24 is cut at the fold line along the juncture between the latching tab 19 and the remainder of the tongue 18 and which may be grasped in manipulating the two latching tongues 19 and 22 for insertion in slots 20 and 23.

On the top edge of the side-forming wing 11c a small handling tab 26 is provided for engagement to facilitate the folding of this side of the box into and out of erected condition, this tab folding over onto the top wall 12 beneath the top flap 13 when the box is in the condition seen in Fig. 1.

Handle means for the box includes the provision of an elongated slot 27 in the top-forming flap 12 and a wide handle-shaped slot 28 in the top-forming extension or tongue 13, there being a tongue 29 in the latter which overlies the slot 27 and which is effective to prevent the bight portion of a U-shaped wire handle 30 from passing down into the box from its carrying condition shown in Fig. 1. The narrow slit 27 is preferably cut with at least one tongue or tooth projecting across the long axis thereof into the complementary cut portion at the opposite side of the slit (Fig. 5), the purpose of this being to provide one or more small tabs 27b which will prevent the bight of the handle from passing back into the box accidentally, the teeth or tabs 27b yielding to permit passage of the handle into and out of the slit under force. The handle has its opposite free end portions 31 bent laterally for stopping engagement with the under side of

the top portion 12 when the bight is inserted through the elongated slot 27.

It is also important to observe that the junc-
tures between the lateral extensions 31 and the
remainder of the handle 30 are offset as at 32 at
right angles so that the handle will more conven-
iently fold back from its upright position of Fig.
1 into a recumbent position substantially within
the handle-shaped slot 28 so that the top portion
13a may be readily folded into open and closed
positions particularly with respect to the inser-
tion of the tongue 29 beneath the bight of the
handle. The slot 27 is preferably narrower than
the handle, and the opposite ends of the slot are
enlarged as at 27a to accommodate the parallel
arm portions of the handle and further facilitate
the rocking movement of the handle from re-
cumbent to upright position. In inserting and
removing the handle from the top flap 12, the
bight portion is gently forced into the constricted
or narrow slot and prevented from dropping out
by the close confrontation of the opposite longi-
tudinal sides of the slot so that ordinarily there
is no danger of the handle dropping down into
the box during manipulation or folding of the
cover part 13a thereof. The utility of the block-
ing tongue 29 is concerned with preventing the
handle from being positively pushed back into the
box through careless or rough handling or when
the slot 27 has become slightly enlarged as a re-
sult of repeated use.

Once the box has been erected and the hinge
strip 17 applied, it may be folded into the condi-
tion illustrated in Fig. 4 for purposes of storage
or portability, the wall portion 11 being pressed
back toward the opposite wall portion 11a and the
bottom 10, the handle folding back closely
against the top portion 12 due to the offsets 32
between the lateral and parallel arm portions
thereof. As a result of this folding feature, mer-
chants may prepare a plurality of the boxes be-
forehand and store the same in a considerably
smaller space than would be required for a cor-

responding number of the usual type of hat box.

It will be obvious that when one of the prepared
boxes is needed, it may be quickly extended from
the condition of Fig. 4 into the assembled or
erected condition of Fig. 1.

In addition to the fact that the box is stamped
from a unitary blank of cardboard or other ma-
terial to provide a blank which folds easily into
box form, the invention provides a box which,
10 once erected or assembled, may subsequently be
collapsed into a compact form ready for instant
use through the simple expediency of erecting the
15 folded form. The interlocking tab feature facil-
itates the opening and closing of the box, and the
enlarged handle-shaped slot formation 28 in the
top, as well as the offset structure 32 of the
handle, greatly facilitate the manipulation of the
top and the blocking tongue 29 for the purpose
aforesaid.

20 The objects and advantages of the invention
may be realized by variations of the foregoing
specifically described construction, and the in-
vention is therefore intended to include all equiva-
lent arrangements fairly coming within the
25 scope of the appended claim.

Having thus described my invention, what I
claim as new and desire to protect by Letters
Patent is:

In a box, a handle structure including the pro-
30 vision of spaced openings in a wall of said box,
and a U shaped handle element comprising a
bight portion joining two parallel side portions
and end portions offset from a plane struck
35 through said bight and side portions and extend-
ing laterally therefrom so as to lie in a plane par-
allel with a plane containing the bight portion of
said handle element, the offset of said end por-
tion permitting the handle element to be rocked
40 substantially in a direction toward and away from
said wall of the box in which the openings are
formed.

WILLIAM TROGMAN.
